CLAIM

The ornamental design for a pistol box, as shown and described.

DESCRIPTIONFIG. 1 is a front, left and top side perspective view of a pistol box showing my new design;
FIG. 2 is a rear, right and top side perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged portion view taken from encircled portion labeled, "FIG. 9," in FIG. 1.

The dashed-dot lines in FIGS. 1 and 9 represent the boundary of the enlarged portion view of FIG. 9 and form no part of the claimed design. The even broken lines in the drawings represent portions of the pistol box that form no part of the claimed design.
